UNITED STATES PATENT OFFICE.

HENRY E. WIEBER, OF KINGSTON, NEW YORK.

DESIGN FOR A STRAINER FOR CATCH-BASINS.

SPECIFICATION forming part of Design No. 28,964, dated June 28, 1898.

Application filed June 3, 1898. Serial No. 682,495. Term of patent 7 years.

To all whom it may concern:

Be it known that I, HENRY E. WIEBER, a citizen of the United States, residing at Kingston, Ulster county, New York, have invented and produced a new and original Design for Strainers for Catch-Basins, of which the following is a specification, reference being had to the accompanying drawings, forming a part thereof.

10 Figure 1 is a side elevation of a strainer for catch-basins, showing my design; and Fig. 2 is a vertical central section of the same.

The leading feature of my invention is a perforated frusto-conical body having a conical crown or top.

15 A indicates the frusto-conical body, which is provided with many perforations *a*, and B

is the conical crown or top, which is provided with perforations *b* and the apex of which has a ring-shaped ornament *C*. At the smaller 20 end of the frusto-conical body *A* is an annular bead *D*, below which is a cylindrical extension *E*.

What I claim is—

The design for a strainer for catch-basins, 25 as herein shown and described.

In testimony that I claim the foregoing as my invention I have signed my name in presence of two subscribing witnesses.

HENRY E. WIEBER.

Witnesses:

PAUL GOEPEL,
GEO. W. JAEKEL.
